MOTOR VEHICLE LIFT

William F. Essex, Chicago, Ill., assignor to Standard Oil Company, Chicago, Ill., a corporation of Indiana

Application March 3, 1934, Serial No. 713,799

10 Claims. (Cl. 254—89)

This invention relates to improvements in motor vehicle lifts and more particularly to improvements in super structure for motor vehicle lifts.

- 5 In the past, motor vehicle lifts of the type used in automotive lubrication service stations wherein the motor vehicle is elevated thereby during the lubricant servicing operation have been constructed with runways lying in a flat 10 horizontal plane upon which the vehicle may be driven and so remain during the time that the lift is in an elevated position. Vehicle lifts of this type require some type of chock for preventing the vehicle from rolling along the runways, such for instance as cross bars placed across 15 the runway at the outer ends of the wheels after the vehicle has been moved into position upon the lift. The positioning of the vehicle upon the runway in the conventional type of 20 motor vehicle lift is left to the discretion of the operator or to the person who drives the vehicle thereupon and although it is most advisable and advantageous that the center of gravity of the 25 vehicle be located directly over the elevating plunger of the lift, the disposition of the center of gravity, or center of mass, of the vehicle over the plunger may only be determined and brought about, if such procedure is practiced at all, by sheer guess work on the part of the operator.
- 30 If the center of gravity of the vehicle is located forwardly or rearwardly of the axis of the lift plunger with respect to the runways, unnecessary friction is developed between the plunger and the packing for the cylinder within which the 35 plunger is operatively mounted. This friction necessitates the expenditure of additional power to elevate the loaded lift. In addition to such waste of power, the unbalanced load upon the lift represented by the disposition of the center 40 of gravity of the vehicle forwardly or rearwardly of the plunger axis may result in mutilation of the cylinder plunger packing, and, in such instances as where the lift is of the rotary type, serious scoring to the side walls of the plunger 45 may result due to the tendency of the plunger to cant with respect to the cylinder, thereupon compressing the packing material and engaging with the packing bushings and adjacent cylinder structure.
- 50 An object of my invention is to provide an improved motor vehicle lift wherein the motor vehicle is automatically located upon the runways to locate the center of gravity or mass of the vehicle directly over the plunger of the lift 55 thereby to balance the load thereupon.

A further object is to provide a motor vehicle lift, as described, wherein the motor vehicle when driven upon the runways thereof adjusts itself thereupon to balance the load thus placed upon the lift with respect to the opposed portions of 60 the runways on either side of the plunger regardless of whether the center of gravity of the vehicle is located centrally of the wheel base of the vehicle or is forwardly or rearwardly of the center of the wheel base.

65 A further object is to provide a motor vehicle lift of the character described which requires a minimum amount of power in elevating the loading lift for a given load.

70 Other objects, the advantages, and uses of the invention will become apparent after reading the following specification and appended claims and after consideration of the drawing forming a part of the specification wherein:

75 Fig. 1 is a side elevation of a motor vehicle lift, incorporating features of my invention;

Fig. 2 is a sectional view along the line II—II of Fig. 1;

Fig. 3 is a sectional view along the line III—III of Fig. 1; and

80 Figs. 4, 5, 6 and 7 are schematic views illustrative of modified forms of the runways for the lift.

85 With reference to Fig. 1, I have illustrated therein a motor vehicle lift having a hydraulic cylinder 1, which may be embedded in the floor of the service station or other enclosure wherein the lift is to be employed, a plunger 2 mounted for movement along the vertical axis within the cylinder 1, suitable packing 3 and packing gland 90 4 being provided to maintain a fluid seal between the cylinder and the plunger. A box type cross member 5 may be secured to the upper end of the plunger 2 to serve as a support for the parallel runways 6. The runways 6 are spaced at 95 a sufficient distance from one another, and are of such width, as to receive the wheels 7 of a motor vehicle thereupon, one of which is indicated at 8 in Fig. 1. Flanges 9 may be formed on the adjacent or inner edges of the runways to guide the 100 vehicle on the runway and to prevent lateral displacement of the vehicle thereupon. Ramps 10 may be hingedly mounted at each end of each runway to assist in the driving of the vehicle upon the runway when the plunger 2 is at the 105 lower limit of its travel.

110 In the form of superstructure, i. e., runways 6, illustrated in Fig. 1, it will be noted that the central portion of the runways from the dotted cross line 11 to the cross line 12 are flat and lie

in a horizontal plane and that the end portions of the runways from points 11 and 12 to the outer ends thereof curve upwardly. The rise of the curved portion thereof above the plane of the central portion of the runways, exclusive of the ramps 10 may be about four inches. In the embodiment shown in Fig. 1, the curved sloping end portions of the runways are preferably circular arcs which are tangent to the flat portions 11—12 10 of the runways.

This formation of the runways, which for the purpose of illustration has been somewhat exaggerated throughout the drawing, provides for the resting of the wheels 7 of the vehicles driven upon the lift upon the sloping portions of the runways. Therefore a vehicle having its center of gravity or mass forwardly of the central portion of the wheel base as represented by the vehicle shown at 8 in Fig. 1 will come to rest upon 15 the runways when permitted to move thereupon, without the retention of the wheel brakes, to a position as illustrated with its center of gravity or mass over the plunger 2. Such disposition of the vehicle, as will be noted, results in the rearward end of the vehicle rising upwardly upon the sloping lift end of the runways whereas the forward end of the vehicle rests at a lower position. If the vehicle were constructed with its 20 center of gravity or mass directly at the midpoint of the wheel base the vehicle would rest with the wheels thereof at equal distances from the plunger.

It will be apparent that with a lift of the character described that the positioning of the vehicle upon the runways, as when it is moved thereupon without the application of the brakes, will depend entirely upon the location of the center of gravity without regard to the physical dimensions of the vehicle. Inasmuch as this functioning of the lift to so locate the vehicle is entirely automatic the operator need only to wait until the vehicle comes to a standstill upon the runways whereafter he may, if he so desires, place suitable chocks upon the runways to preclude accidental shifting of the vehicle as during the servicing operation, although it will be quite apparent that the tendency of the vehicle to shift longitudinally upon the runways will be resisted to a marked degree due to the fact that in order to 45 so shift in either direction the center of gravity of the vehicle must be elevated.

In Fig. 4 I have illustrated another form of the runway structure wherein the runways are of uniform curvature throughout as indicated at 6a, 50 the curvature thereof being developed about centers lying in a plane including the axis of the plunger 2. I prefer to employ a radius of such length as to locate the remote ends of the runways at a distance not more than 4" above the lowest or mid-point of the runways. In this figure, as well as the remaining figures of the drawing, I have exaggerated the curvature of the runways for the purpose of illustration.

The runway construction illustrated in Fig. 5 is 55 identical to that of Fig. 4 with the exception that the mid-portion of the runways as shown at 13 are horizontal and of a length less than the length of the wheel base of the vehicle to be supported thereupon. The advantage of this construction over that of Fig. 4 is that the remote 60 ends of the runways may be located closer to the floor or the supporting surface within which the lift cylinder 1 is embedded thereby to facilitate the movement of the vehicle to and from the 70 runways.

In operation the lift superstructure of Figs. 4 and 5 is similar to that of Fig. 1, the constantly increasing angle of the slope of curvature toward the remote ends of the lift serving to urge the vehicle to shift upon the runways to bring the center of gravity or mass thereof over the mid-point of the runways over the axis of the plunger 2. 80

In Fig. 6 I have illustrated a further modification of the runway structure wherein the runways 6b are curved, the form of the curve being such that the radius of curvature continually decreases from a maximum at the center of the runway to a minimum at the outer ends. Such a form of curve may be developed by well known mathematical methods. Among the types of 90 mathematically devised curves which might be utilized are the ellipse, parabola, hyperbola, cycloid, trocloid and various spirals. 95

I have illustrated in Fig. 7 a further modification of the runway structure wherein as in the case of the structure of Fig. 6, the outer ends thereof except that as in the case of the runways of Fig. 5, the mid-portion 14 of the runways for a distance less than the wheel base 100 of the vehicle to be supported are flat and lie in a horizontal plane.

While I have described a preferred example of my invention it should be understood that I do not limit myself to the details hereinabove 105 set forth except as defined by the following claims.

I claim:

1. A motor vehicle lift comprising, a movable lift plunger, and a motor vehicle runway supported upon said plunger, said runway lying in a substantially horizontal plane and having those portions thereof upon which the wheels of a vehicle rest when upon said runway sloping upwardly from the mid-portion of the runway at 110 a constantly increasing angle.

2. A motor vehicle lift comprising, a vertically movable lift plunger, and a motor vehicle runway supported at its mid-point upon said plunger, said runway having those portions upon which the wheels of a vehicle may rest when upon the runway curved upwardly in the direction of the ends of the runway, the curvature of each of 120 said portions being the same.

3. A motor vehicle lift, comprising a vertically 125 movable lift plunger, and a motor vehicle runway supported at its mid-point upon said plunger, said runway lying in a substantially horizontal plane and sloping upwardly at its opposite end portions at a constantly increasing angle 130 toward the adjacent ends of the runway.

4. A motor vehicle lift as defined in claim 2 wherein the radius of curvature of said runway portions is constant.

5. A motor vehicle lift as defined in claim 2 135 wherein the said runway portions are in the form of circular arcs having a common center.

6. A motor vehicle lift as defined in claim 2 wherein the curvature of said runway portions is variable and developed from a common point. 140

7. A motor vehicle lift as defined in claim 2 wherein the radius of curvature of said runway portions gradually decreases in the direction of the remote ends of the runway.

8. In a motor vehicle lift, a runway supported 145 at its mid-point, said runway being curved to present an upwardly facing surface of concave curvature upon which the wheels of a motor vehicle may rest thereby to locate the center of gravity of the vehicle over the mid-point of the 150

runway when the vehicle is free to roll there-
upon.

9. In a motor vehicle lift a motor vehicle run-
way supported at its mid-point, said runway hav-
ing its central portion lying in a horizontal plane
for a distance not greater than the wheel base
of a vehicle to be supported thereupon and hav-
ing its end portions sloping upwardly away from

the said horizontal portion at a constantly in-
creasing angle from horizontal.

10. In a motor vehicle lift, a motor vehicle
runway as defined in claim 9 wherein the remote
ends of the runway are located not more than 30
four inches above said horizontal portion.
